UNITED STATES PATENT OFFICE

99,893

DESIGN FOR A PAPER PAIL OR THE LIKE

Wilbert A. Rike, Neenah, Wis., assignor to Marathon Paper Mills Company, Rothschild, Wis., a corporation of Wisconsin

Application April 3, 1936, Serial No. 61,922

Term of patent 7 years

To all whom it may concern:

Be it known that I, Wilbert A. Rike, a citizen of the United States, residing at Neenah, in the county of Winnebago and State of Wisconsin, have invented a new, original, and ornamental Design for a Paper Pail or the like, of which the following is a specification, reference being had to the accompanying drawing, forming a part thereof.

Figure 3 is an elevational view showing in detail the ornamentation as it appears on each of the narrower faces thereof.

I claim:

The ornamental design for a paper pail or the like, as shown and described.

In testimony whereof I affix my signature.

WILBERT A. RIKE.
